UNITED STATES PATENT OFFICE.

ISAAC OSGOOD, OF AMESBURY, MASSACHUSETTS.

THILL-COUPING.

SPECIFICATION forming part of Letters Patent No. 733,869, dated July 14, 1903.

Application filed March 20, 1902. Serial No. 99,113. (No model.)

To all whom it may concern:

Be it known that I, ISAAC OSGOOD, a citizen of the United States, residing at Amesbury, in the county of Essex, State of Massachusetts, have invented a certain new and useful Improvement in Thill-Couplings, of which the following is a specification, reference being had therein to the accompanying drawings.

10 The invention has relation more especially to thill-couplings of that class in which a toggle-like action of the parts is utilized, and has for its general aims to produce a more convenient and practical thill-coupling than 15 has heretofore been known, as well as to secure certain advantages in use over preexisting thill-couplings.

The principles of my invention are capable of being embodied in more or less varied form, 20 although I have represented in the drawings the best form in which I have thus far embodied the invention.

In the drawings, Figure 1 shows the said embodiment of the invention in side elevation in closed condition. Fig. 2 is a similar view showing the same in open condition. Fig. 3 is a detail view in section on line 3 3 of Fig. 2. Fig. 4 shows the operating-lever in elevation detached.

30 A thill-coupling embodying my invention comprises, essentially, a fixed jaw 1; a movable jaw 2, an operating-lever 3, and a link 4. The parts are operatively combined by pivotally connecting the operating-lever 3 and link 4, respectively, to the movable jaw 2 and to a fixture, respectively, as at *a c*, and also connecting them pivotally with each other, as at *b*. The said fixture usually is constituted by a continuation of the fixed

40 jaw 1. Ordinarily and preferably the features of the invention are employed in connection with the thill-iron 5, the fixed jaw 1 being fixedly applied to the latter or integral therewith, so that the thill-iron constitutes a 45 continuation of the fixed jaw 1, and the movable jaw 2 being pivoted, as at *d*, to the fixed jaw or other portion of the thill-iron, although the invention in some of its embodiments is not limited in this respect.

50 The operating-lever 3 and link 4 constitute a toggle interposed between the movable jaw 2 and the thill-iron and enable the said mov-

able jaw to be opened and closed through the application of power to the free arm or operating-handle 31 of said lever. When the said lever is swung into position to straighten the toggle, as in Fig. 1, the movable jaw is thereby caused to close toward the fixed jaw, as in the said figure. When the lever is caused to assume the position which it occupies in Fig. 2, the toggle is bent, and thereby the movable jaw is caused to separate from the fixed jaw. Usually, but not necessarily in all embodiments of the broad principles of the invention, the lever 3 is pivoted to the movable 65 jaw 2 and the link 4 is pivoted to the thill-iron. This arrangement is preferred, inasmuch as it enables the free arm or operating-handle 31 of the lever 3 to lie closely against the under side of the thill-iron out of the way 70 when the thill-coupling is closed, while inasmuch as in such position the said free arm or operating-handle 31 extends forwardly along the under side of the thill it is readily accessible to enable it to be grasped and manipulated for the purpose of opening the thill-coupling.

A characteristic feature of the toggle arrangement is the fact that the centers *a b c* are so-arranged with relation to one another 80 that in moving the lever 3, so as to cause the parts to assume the closed position, which is represented in Fig. 1, the center *b* is carried slightly past or beyond the straight line connecting the centers *a c* with each other. So 85 long as center *b* occupies this position relative to centers *a c* the movable jaw 2 is locked positively in its closed position against the action of force tending to press it away from the fixed jaw 1. Preferably, also, the arrangement of centers *d a b* with relation to one another is such that in the fully-opened position of the parts the center *a* will be carried slightly past a straight line connecting the centers *d b*.

95 For the purpose of insuring against too free a movement of the operating-lever from either of its extreme positions the tension of a spring is utilized in connection therewith. The spring may be applied and combined variously in practice; but preferably it is arranged and caused to act as in the drawings. In the latter the thill-iron is formed with a longitudinal cavity or recess 51, and within

the latter is contained a blade or leaf-spring 6, the latter being somewhat bowed or bent longitudinally, so that its middle tends to project below its opposite ends. The said spring 6 is secured within the cavity or recess 51 in any suitable manner. Herein the spring is placed loosely within the cavity or recess 51 and is retained in place by the tail of link 4. The link 4 is furnished with a tail 41, which is arranged in position to be borne against by the middle portion of spring 6. The pressure of the spring against the said tail 41 tends to hold the parts in the closed position, which is shown in Fig. 1, and to keep the center *b* above the line which passes through centers *a c*. When the lever 3 is moved to open the thill-coupling, the action of tail 41 of link 4 against the spring 6 increases the tension of the latter. In the fully-opened position of the parts, which is represented in Fig. 2, the pressure of the spring against the tail 41 tends to turn the link 4 in a direction to carry the center *b* toward the center *d*. The pressure of the spring in this position of the parts tends to hold center *a* beyond a straight line, connecting centers *d* and *b*, and thereby yielding locks the coupling in its open condition. The operating-lever 3 swings forward and rearward in the same vertical plane that is occupied by the thill-iron.

For the purpose of preventing access of dust, mud, water, &c., to the spring 6 and to the portions of said spring and of the tail 41 which work in contact with each other and to the bearings at the opposite ends of the link the spring 6 is placed within the longitudinal cavity or recess 51, that is formed in the thill-iron, and the operating-lever 3 is shaped and fitted so that it closes down over the said cavity or recess, so as to constitute in the closed condition of the coupling a cover for the spring, the link, and the cavity or recess in which the spring is contained and within which the tail of the link works. The lever 3 is formed adjacent its fulcrum *a* with lateral flanges 31 31, between which the link 4 is pivoted at *b*, and in the closed position of the parts the said flanges completely inclose the main portion of the link. The lever 3 is recessed at 32 to receive the hub 42 of the link adjacent the pivot or center *c*.

The free forward extremity of the lever 3 is furnished with an open or U-shaped guide, formed by opposite lugs or lips 33 33 on the said extremity. Within the said guide is received the safety-strap 7. The latter is shown looped around a cross-pin 8, riveted to lugs 9 9, formed integral with the thill-iron. The thill and thill-iron are shown fastened together near the forward end of the thill-iron by means of a screw 10. The rear end of the thill is shown fitted within a socket formed for its reception between side lips 11 11, with which the thill-iron is formed, the said side lips having ears or lugs 12 12 rising therefrom. Usually these ears or lugs stand up straight before the thill and thill-iron are

connected with each other. After the thill and thill-iron have been fitted together and secured by the screw 10 the said ears or lugs are hammered down over the end of the thill, so as to securely clasp the said end. This construction enables the use of bolts or screws passing through the end of the thill to be avoided, if deemed advisable. These various features of construction are not in themselves material to the invention.

It will be apparent that by pivoting the lever to the movable jaw and arranging the lever so that it shall swing forwardly and close up against the under side of the thill-iron the said lever is not in the way of the safety-strap 7. (See Fig. 1.)

I claim as my invention—

1. The thill-coupling comprising, essentially, the thill-iron provided with the fixed jaw, and the movable jaw, and in combination therewith the operating-lever and link connected with the movable jaw and the thill-iron, and also connected with each other, the said lever and link operating the movable jaw to open and close the latter and also constituting a toggle whereby the movable jaw is locked in its closed position.

2. The thill-coupling comprising, essentially, the thill-iron provided with the fixed jaw, and the movable jaw, and in combination therewith the operating-lever and link connected with the movable jaw and the thill-iron, and also connected with each other, the said lever and link operating the movable jaw to open and close the latter and also constituting a toggle whereby the movable jaw is locked in its closed position, and the spring operatively engaging with an eccentric portion of one of said parts to hold the parts in position.

3. The thill-coupling comprising, essentially, the thill-iron provided with the fixed jaw, the movable jaw, the operating-lever and link connected with the movable jaw and thill-iron, and also connected with each other, and the spring operatively engaging with one of said parts to hold the parts in position, the said lever and link operating the movable jaw to open and close the latter, and the parts being arranged to lock the movable jaw in its open and closed positions, respectively.

4. The thill-coupling comprising, essentially, the thill-iron provided with the fixed jaw, the movable jaw, the operating-lever and link located between their points of connection with the said movable jaw and thill-iron, and the spring operatively engaging with one of said parts to hold the parts in position.

5. The thill-coupling comprising, essentially, the thill-iron provided with the fixed jaw, the movable jaw, the operating-lever and link located between their points of connection with the said movable jaw and the thill-iron, and the spring operatively engaging with one of said parts, the parts being arranged to be held locked in open and closed positions, respectively, by the action of the spring.

6. The thill-coupling comprising, essentially, the thill-iron provided with the fixed jaw, the movable jaw, the lever and link whereby said movable jaw is operated, and 5 the separate spring coacting with the tail pertaining to one of the said parts for operating the movable jaw.

7. The thill-coupling comprising, essentially, the thill-iron provided with the fixed 10 jaw, the movable jaw, the lever and link for operating the movable jaw, and the spring coacting with the tail pertaining to one of the said parts for operating the movable jaw, the pivotal centers of the points of connection being arranged to cause the parts to lock in the 15 closed and open positions of the movable jaw, respectively.

8. The improved thill-coupling comprising, essentially, the thill-iron provided with the 20 fixed jaw and having the spring-receiving cavity, the movable jaw, the lever and link, and the spring operatively engaging with one of the movable parts, the said lever in its closed positions covering the said cavity and the 25 spring and link contained therein.

9. The improved thill-coupling comprising, essentially, the thill-iron provided with the

fixed jaw, the movable jaw, the link pivoted to the thill-iron, and the lever having said link pivotally connected thereto, itself piv- 30 oted to the movable jaw, and arranged to close forwardly against the under side of the thill-iron.

10. In a thill-coupling, in combination, the thill-iron and the fixed jaw, the movable jaw, 35 and actuating devices for said movable jaw provided with an operating-lever pivoted directly to the movable jaw.

11. In a thill-coupling, in combination, the thill-iron and the fixed jaw, the movable jaw, 40 and actuating devices for said movable jaw provided with an operating-lever pivoted directly to the movable jaw, the said movable jaw being pivoted to the fixed jaw at one point and to the operating-lever at another, and 45 said lever being pivotally connected with the movable jaw at one point and having also a pivotal support at a second point.

In testimony whereof I affix my signature in presence of two witnesses.

ISAAC OSGOOD.
